Primary Examiner — Jack Reickel*Assistant Examiner* — Sydney M Evans(74) *Attorney, Agent, or Firm* — Global IP Counselors, LLP(57) **CLAIM**

The ornamental design for a portable electric driver body as shown and described.

DESCRIPTION

FIG. 1 is a front, left and top perspective view of a portable electric driver body showing my new design; FIG. 2 is a front elevational view thereof; FIG. 3 is a rear elevational view thereof; FIG. 4 is a top plan view thereof; FIG. 5 is a bottom plan view thereof; FIG. 6 is a left side elevational view thereof; and, FIG. 7 is a right side elevational view thereof.

The broken lines in the drawings illustrate portions of the portable electric driver body which form no part of the claimed design. The dash dot dash lines represent the boundary of the claimed design and form no part of the claimed design. The faded portions outside the dash dot dash line and inside the broken line illustrate portions of the portable electric driver body that form no part of the claimed design.
